MANDIBLE DEVELOPER

Corman O. Edwards, Oakland, Calif.

Application May 22, 1933, Serial No. 672,171

10 Claims.

(Cl. 128—76)

This invention relates to a device for the correction of mal-formations in children, and more particularly to a device for correcting an under-developed or improperly formed mandible or 5 lower jaw.

It is not uncommon for a child to be born with a lower jaw or mandible that, due to hereditary, prenatal, or other causes is shorter than normal and, in fact, in many cases falls far short of 10 proper position in relation to the maxilla or upper jaw. The result in such cases, where no attention is given to the improper formation, is that the dental arches occurring later in life are not so aligned as to cooperate properly in 15 mastication, and in many cases the dentition and, in fact, the entire face of the person affected is so badly shaped as to cause a pronounced deformity in outward appearance.

Under present methods of correction it is 20 often necessary in cases of poorly developed mandible or lower jaw to wait until the child is well along toward the adolescent age and then proceed upon principles of orthodontia well known to the medical and dental professions.

It is the object of the present invention to 25 provide a device, by means of which the mandible may be developed starting from the time of birth or very shortly thereafter and continuing for whatever period of time is necessary according to the condition of the individual. The 30 object of the invention also includes the provision of a device of this nature that is simple mechanically, inexpensive to manufacture, and capable of ready adjustment to accommodate 35 variations in the acuteness of the deformity in different patients, as well as growth and development in the individual patient.

These objects are accomplished by means of a 40 small plate and means for securing the plate to a nursing bottle in such a position near the nipple of the bottle that it will bear against the upper lip of the infant using the bottle. The means for connecting the plate to the bottle are such that the position of the plate relative to the 45 nipple and lengthwise thereof may be adjusted to accommodate cases of varying degrees of acuteness.

In practice, the infant using the nursing bottle is forced to reach forwardly with the mandible 50 to enable it to suck on the nipple, the plate on the device serving as a barrier to prevent the nipple from being taken into the mouth without the forward thrust of the mandible.

Experiments have proven that in constantly 55 reaching in this manner the growth of the man-

dible is stimulated, and that in time (the length of time required depending, of course, upon the individual case) the mandible becomes normal in size and proper in its position relative to the maxilla or upper jaw. This development, it should be understood, takes place before the period of first dentition so that the teeth are not improperly positioned upon their eruption. 5

One form of my invention is illustrated in the accompanying drawing, and the same is described in greater detail in the following specification, upon reading which other objects of the invention will become apparent.

In the drawing—
Fig. 1 is a view in side elevation of a nursing bottle fitted with a mandible developer constructed in accordance with my invention;

Fig. 2 is a perspective view of the mandible developer in slightly different form;

Fig. 3 is an enlarged fragmentary view of a 20 portion of the device taken on the central vertical longitudinal plane of Fig. 1;

Fig. 4 is a plan view of the portion of the device shown in Fig. 3; and

Fig. 5 is a perspective fragmentary view showing a modified form of the invention.

Referring more particularly to the drawing, I show, in Fig. 1, a nursing bottle 9 of conventional design fitted with the usual nipple, as indicated at 10. A small plate 11, a detailed description of which will follow, is supported in a position adjacent to the nipple 10 by any suitable means in the position required by the circumstances of the particular case. A preferred means for supporting the plate is shown as an arm 12, to one end of which the plate 11 is secured in any suitable manner. The other end of the arm 12 is suitably attached, as for example by soldering, brazing, or the like, to a band 13 which encircles the bottle. The band 13 has ends 14 and 15 bent outwardly; the end 14 being perforated and the end 15 being likewise perforated and tapped for the reception of a screw 16 fitted with a knurled head for convenience in turning the screw to tighten it. 40

Tightening of the screw 16 will draw the ends 45 14 and 15 of the band 13 toward each other, thereby causing the band to engage the bottle frictionally and with sufficient force to support the arm 12 and plate 11 rigidly in a fixed position relative to the bottle and nipple.

In using the mandible developer, the device as described above is fitted to a nursing bottle in the manner and position illustrated in Fig. 1. The infant to be treated is then permitted to take the 50 contents of the bottle by sucking upon the nipple 55

in the ordinary manner; the bottle meanwhile being held in a position to cause the plate 11 to bear against the upper lip of the infant, preferably about midway between the nose and mouth. 5 Thus the plate 11 limits the distance to which the nipple may be taken into the mouth and the infant with a receding or under-developed lower jaw must thrust the jaw forwardly in order to take food through the nipple.

10 Continual feeding from a nursing bottle fitted with the mandible developer results in growth or development of the lower jaw until it obtains normal size and a proper position relative to the upper jaw.

15 Referring again to Fig. 1 of the drawing, the arm 12 is shown as having a portion 17 adjacent to the plate 11 that is curved slightly in the direction of the nipple. This curve is provided so that the infant's nose which extends over the plate 11 when 20 the device is being used will not bear against the arm at this point.

The several parts of the device may be made of any suitable metal, preferably polished and plated for the sake of sanitation, but I prefer that the 25 arm 12 be formed of relatively soft brass or other metal sufficiently ductile to permit its being shaped by bending so as to adapt the position of the plate 11 to the particular needs of the individual patient. The band 13 and screw 16 permit 30 adjustment of the device longitudinally of the bottle which is of great importance as by such adjustment the infant may be caused to thrust the jaw forwardly more or less as may be required to obtain the development desired. In acute cases 35 it will be readily understood that the development must be accomplished in stages, the plate 11 being first positioned in a retracted position and then gradually advanced toward the distal end of the nipple as the development proceeds.

40 In Fig. 2 of the drawing, I have shown the band 13 as generally octagonal in shape to fit the standard octagonal nursing bottle, and the band may be made in any desired shape according to the type of bottle with which it is to be used.

45 The form of the plate 11 is best illustrated in Figs. 3 and 4 wherein it is shown as generally rectangular with rounded corners and slightly dished to conform to the shape of the upper lip, against which it rests, as comfortably as possible. 50 The plate may also be slightly narrower at its central portion than at its ends, as shown, to insure against contact of the upper edge against the nose of the infant.

55 As stated above, it is contemplated that adjustment of the position of the plate 11 will be made to accommodate individual infants, and in order that such adjustment may be accomplished more readily than by bending of the arm 12, I have illustrated a modified form of adjusting means in Fig. 60 5 of the drawing.

In Fig. 5 the arm 12 is made in two sections, the ends of which are flattened and perforated for the reception of a screw 18, about which the arms are relatively pivotable. Upon loosening the 65 screw 18, the plate 11 will be free to swing to a position of desired adjustment and it may be fixed in such position by tightening the screw.

70 From the foregoing it will be apparent that I have provided a device that is very useful for the purpose described, that is simple to apply to a nursing bottle, and is so constructed that it may easily be removed and sterilized at frequent intervals.

Treatment with the device may be administered 75 by any person capable of feeding and caring for

an infant in ordinary respects. It is preferable, however, that the device be used only under the advice and direction of a doctor or person highly skilled in the art. The adjustments necessary and the extent and duration of use of the mandible developer are for the discretion of the doctor, but it may be stated here that its use may be started with the earliest bottle feeding and, when necessary, continued for some time after the infant is taking solid foods, as all of the required 10 liquids, including water, may be taken from a bottle fitted with the device.

15 While I have illustrated and described a preferred form of my invention, it should be understood that various changes may be resorted to in the construction and arrangement of its several parts within the spirit and scope of the appended claims.

Having thus described my invention, what I claim and desire to secure by Letters Patent is:— 20

1. The combination with a nipple through which an infant sucks food, of a plate, and means to support said plate in a position adjacent to said nipple to contact the upper lip only of the infant, whereby the nipple may be taken into the 25 mouth only when the lower jaw is thrust forwardly.

2. The combination with a nursing bottle and a nipple therefor of a device for developing the lower jaw of an infant, which comprises a plate positioned adjacent to the nipple of said nursing bottle to bear against the upper lip only of an infant sucking the nipple, whereby the lower jaw of the infant must be thrust forwardly to enable it to suck upon the nipple. 30

3. The combination with a nursing bottle and a nipple therefor of a device for developing the lower jaw of an infant, which comprises a lip-engaging plate positioned adjacent to the nipple of said nursing bottle and engageable with the 40 upper lip of an infant sucking the nipple.

4. The combination with a nursing bottle and a nipple therefor of a device for developing the lower jaw of an infant, which comprises a lip-engaging plate positioned adjacent to the nipple 45 of said nursing bottle and engageable with the upper lip only of an infant sucking the nipple, and a support for said means carried by the said bottle.

5. The combination with a nursing bottle and a nipple therefor of a device for developing the lower jaw of an infant, which comprises a plate positioned adjacent to the nipple of said nursing bottle and engageable with the upper lip of an infant sucking the nipple, a support for said plate carried by the bottle, and means for adjusting said support longitudinally of the bottle. 50

6. A device for developing the mandible in infants, which comprises a band adapted to surround a nursing bottle having the usual nipple, 60 an arm supported by said band, and a plate carried by said arm and held thereby in a position adjacent to a nipple on the bottle for engagement with the face of an infant using the nipple to cause the infant to thrust its mandible forwardly when sucking on the nipple.

7. The combination with a nursing bottle having the usual nipple, of a plate supported by the bottle in a position adjacent to the nipple to contact the face of an infant using the bottle, said 70 plate being positioned to cause the infant to thrust its lower jaw forwardly in order to take the nipple into its mouth.

8. A device for developing the mandible in infants, which comprises in combination a nursing 75

- bottle having the usual nipple, a band surrounding the bottle and fixed thereon for longitudinal adjustment relative thereto, an arm supported by said band and extending to a point adjacent to 5 said nipple, a plate carried by said arm for engagement with the face of an infant using the nipple, and a hinged joint in said arm whereby said plate may be adjusted in its position relative to the nipple.
10. 9. A device for developing the mandible in infants, which comprises in combination a nursing bottle having the usual nipple, a band surrounding the bottle and fixed thereon for longitudinal adjustment relative thereto, an arm supported by 15 said band and extending to a point adjacent to said nipple, and a plate carried by said arm for

engagement with the face of an infant using the nipple, said arm being formed of material sufficiently ductile to permit its being bent to adjust the position of said plate relative to the nipple.

10. A device for developing the lower jaw of an infant which comprises, in combination with a nursing bottle having the usual nipple, a plate engageable with the upper lip of the infant, means carried by the bottle for supporting said plate in a position adjacent the nipple so as to cause the infant to thrust forward the lower jaw in order to suck upon the nipple, and means for adjusting the position of said plate relative to the nipple to vary the distance that the jaw must be thrust forwardly.
